UNITED STATES PATENT OFFICE.

CHARLES HARMAN FIELD, OF DALTON, GEORGIA.

BALING-PRESS.

SPECIFICATION forming part of Letters Patent No. 533,353, dated January 29, 1895.

Application filed December 1, 1893. Serial No. 492,491. (No model.)

To all whom it may concern:

Be it known that I, CHARLES HARMAN FIELD, a citizen of the United States, residing at Dalton, in the county of Whitfield and 5 State of Georgia, have invented a new and useful Baling-Press, of which the following is a specification.

My invention relates to improvements in baling-presses, the objects in view being to 10 produce a baling-press of simple construction and adapted to be operated by horse, steam or other power; to provide a convenient mechanism for operating the plunger, which is so constructed as not to increase the draft on 15 the horse at the final portion of its stroke, but which will be steady, smooth, and even, and which will cause the plunger to move fast at the beginning of the stroke and gradually decrease its speed toward the end of the stroke 20 and at the latter time increase the leverage, whereby a greater amount of power is yielded at the time that the packing of the bale takes place; and, furthermore, to absorb the rebound of the plunger, preventing the shock 25 to the machine as caused by the rebound and gradually returning the plunger to its position for a subsequent stroke.

Other objects and advantages of the invention will appear in the following description 30 and the novel features thereof will be particularly pointed out in the claims.

Referring to the drawings:—Figure 1 is a perspective view of a press embodying my invention. Fig. 2 is a sectional view through 35 the baling-chamber, the power mechanism being shown in side elevation. Fig. 3 is a transverse sectional view of the press in advance of the tucker-roll. Fig. 4 is a detail in perspective of the tucker-roll and its support. Fig. 5 is a detail in perspective of the power- 40 mechanism, the operating lever being removed and indicated by dotted lines. Fig. 6 is an inverted plan view of the lever. Fig. 7 is a horizontal sectional view through the 45 power-mechanism. Fig. 8 is a detail view of the end of the plunger head. Fig. 9 is a horizontal section on the line 9—9, Fig. 2. Fig. 10 is a detail view of one of the detents and its supporting casing. 50 Like numerals of reference indicate like parts in all the figures of the drawings.

The press chamber may be of any suitable

construction, but is preferably constructed as follows: I employ transverse sills 1, from the two front ones of which there arise pairs of 55 vertical standards 2, the same being connected by superimposed sills 3, through the ends of which and the sills 1 tie-rods 4 are passed. A rear superimposed sill 5 is arranged over the rear sill 1 and tie-rods 6 pass through the ends 50 of the sills 1 and 5 as shown. Upon the sills 1 is supported the bottom 7 and the opposite side walls 8, and between the latter is located the roof 9, which is removed or cut away between the superimposed sills 3. 65

It will be obvious that inasmuch as the side walls are partially removed between the two rear sills the roof and bottom will be sprung together by means of the nuts 10 arranged on the upper ends of the vertical tie-rods 6, 70 and thus the exit or discharge end of the baling-chamber may be decreased or increased in size, as necessity may require, while baling is being done with the machine.

In advance of the intermediate sill 1, the 75 sides 8 of the baling-chamber are longitudinally or horizontally slotted and pivotally arranged in these slots are opposite vertical series of tapering wedge-shaped detents. The fulcrum end of each detent 11 is pivoted in a 80 U-shaped casing 57 and these casings together with the detents are seated in the series of slots, the casings being maintained in the slots by means of the metal strips 57^a applied to the exterior of the chamber. If at 85 any time a detent should break it would require simply a removal of the strip 57^a to permit of its withdrawal. Vertical yokes 12 are applied to the outer surfaces of the sides 8, and coiled springs 13 are interposed between 90 the yokes and the free ends of the aforesaid detents, whereby they are yieldingly pressed inward.

A pair of brackets 14 are secured to the upper side of the intermediate superimposed 95 sill 3 and extend forward over the feed-opening in the upper side of the baling-chamber. A pivoted arm 15 is secured to the rear side of the superimposed sill between the brackets 14^a and extends forward in line with the 100 same. This arm 15 has its front end pivoted at 15^a to a pair of bearing-ears 17 formed on the upper side of a tucker-bar 18 between whose upper side and the brackets 14 coiled

springs 19 are interposed. The tucker-bar has its opposite ends provided with forwardly extended bearing-ears 20, and journaled in said ears is a transversely disposed tucker-roll 21 whose axis projects beyond the bearing-ears and has its ends connected pivotally with a pair of arms or levers 22 which have their front ends pivoted at 23 to the inner sides of the side-walls 8 of the baling-chamber 10 such arms being located in recesses formed in the side-walls of said baling-chamber for their reception. I thus produce a very efficient tucking device, which by reason of the presence of the roll facilitates the movements 15 thereunder of the plunger in a manner that will be obvious, the roll and bar serving their usual functions of tucking the material. The detents at the sides of the chamber also serve their usual function and prevent a with- 20 drawal of the material being baled by a retraction of the plunger.

24 designates the plunger head, which may be of any desired construction, and has secured to its rear side a bracket casting 60 to 25 which is pivoted as at 25, the end of the plunger-beam 26, the same being normally withdrawn together with the head by means of a coiled spring 27 attached at one end to the plunger-beam and at the opposite end to 30 one of a pair of longitudinal beams or sills 28 which are secured to the beams of the baling chamber in the usual manner. The upper side of the plunger-head has a sheet metal plate or covering 24^a, the front of which 35 is inclined as at 58 and provided with a transversely disposed angular portion 72 to facilitate the passage of the head under the roll and prevent clogging of the hay at the roll, and which also facilitates the rebounding of 40 the plunger.

45 The outer ends of the beams or sills 28 are supported in cross-sills 29, and arranged thereupon is a metal base-plate 30. This base-plate 30 is securely bolted to the sills 28 and 29, and has formed upon its under side a transverse rib 30^a which engages with a kerf in the sills 28 and relieves the bolts from excessive strain, and also has formed upon its upper side near its front end a vertical post 50 31 which forms one end of a longitudinally disposed metal frame 32. The post 31 is bored and receives a stud 33 which passes centrally through a flanged opening 34 formed at the center of a compoundly curved lever 35. This 55 lever is preferably provided upon its upper side with strengthening ribs 36 and may be provided with one or a number of compoundly curved cam-flanges 37. The flanges are not regularly curved but at their outer ends are 60 more abrupt than at their inner ends as shown, and are each disposed in a similar direction. Arranged upon the lever 35 is the sweep-arm 38 to which the usual draft-appliances may be connected.

65 A socket 39 is fitted on the outer end of the plunger-beam 26, said socket being bifurcated at its extremity and having passed there-

through a vertical pin 40, the upper end of which projects above the socket and is provided with an anti-friction roller 41 arranged 70 in the circular path traversed by the cam-flanges as the lever 35 moves upon its pivot 33. Between the branches of the bifurcations I pivot upon the bolt 40 a link 42, whose remaining end terminates in a transversely 75 bored head 43 located within the frame 32 and pivoted to the latter at one side of the post 31 by a bolt 44. That end of the link 42 which is pivoted to the plunger is provided at one side with a curved wearing-shoe 46. 80

Securely bolted to the outer end of the frame 32 is a quadrant shaped arm 47, the same extending around to the opposite side of the plunger-beam and being supported by brackets 50 which rise from the outer sill 29 85 and the adjacent longitudinal sill 28. A curved spring buffer-plate 51 is secured to the outer end of this segment-shaped arm, is doubled upon itself at the inner side of the arm following substantially the curvature 90 thereof, and terminates short of the opposite end, where it is provided with an off-set 52 arranged opposite a threaded perforation 53 formed in said arm. An adjusting-screw 54 passes through the perforation 53 and terminates at its front end in a head 55 between which and the off-set there is arranged a coiled spring 56. The spring-plate is disposed eccentrically with relation to the pivot-bolt 44 of the link 42, and is in such position as to 100 receive the impact of the shoe 46 when the plunger-beam rebounds.

In operation the hay or other material to be baled, is fed through the feed-opening in the roof of the press into the path of the plunger-head and the team started. The sweep 105 38 together with the lever 35 are revolved upon the post 31 and the cam-flanges on the under side of the lever 35 are successively brought into contact with the anti-friction roller 41 at the extreme end of the plunger-beam. By reason of the disposition or curvature of each of these flanges, and the relative locations of the points of pivot of the lever 35 and link 42, the plunger-beam is 110 moved rapidly at the beginning of its stroke and gradually, but with more power, toward the end thereof, and actuates the plunger-head to carry the material back into the chamber in the usual manner. The limit of 115 movement of the plunger-beam is of course in accordance with the length of the flanges which are, as will be obvious, successively brought into operative position in connection with the end of the beam. As soon as the 120 anti-friction roller has traversed over one of the flanges and it reaches the end thereof, the lever 35 of course continuing its movement the plunger-beam is released from the presence of the flange and the retracing spring 125 27 serves to return the plunger. The fulcrum point of the lever 35, which is its post 31, and the link 42, which is its post 130 43 are eccentrically located with reference

to one another, both being in line with the baling-chamber. The outer end 62 of the curved flange 37 first comes in contact with the roller 41 and the latter is by the sweep 5 of the lever carried toward the fulcrum of said lever. Of course, the nearer it approaches the post 31 the greater the leverage which it will be seen occurs at the last part of the stroke. The sudden retraction of the 10 plunger which is necessary in order to return the same to a position for again operating, it is desirable to absorb and thus prevent the shock of the impact of the same. For this purpose I provide the buffer-mechanism 15 which I have described, and it will be seen that as the plunger returns the shoe 46 will come in contact with the front end of the spring-plate, and it being set eccentrically with relation to the pivot point of the link 20 and consequently the center upon which the end of the plunger is moving will by reason of the frictional contact between the shoe and the plate cause the momentum to be gradually overcome and the rebound thus absorbed. The spring-plate is but yieldingly 25 supported in the path of the shoe and hence will yield so that the return of the plunger to its normal position is almost noiseless and practically but little concussion takes place. 30 Of course the number of cam-flanges of the lever 35 may be varied. I have illustrated two, but one might be used, or any number, the lever being varied in shape to accommodate them in a manner that will be obvious. 35 From the foregoing description in connection with the accompanying drawings it will be seen that I have provided a very simple, strong and durable press, whose plunger may be actuated a number of times to one complete circle traversed by the draft-animal; whose power is increased by reason of the disposition of the curved flanges without increasing the draft upon the horse, and at a time when it is necessary, namely, at the end 40 of the stroke of the plunger; and wherein the shock or concussion caused by the return of the plunger is practically and effectually absorbed.

I do not limit my invention to the precise 50 details of construction herein shown and described, but hold that I may vary the same to any degree and extent within the knowledge of the skilled mechanic.

Having described my invention, what I 55 claim is—

1. In a baling-press, the combination with a baling-chamber having a feed-opening upon its upper side, of a pair of brackets secured rigidly to the press and extending forward 60 over the opening, an arm pivoted at its rear end between the brackets and projecting in line with the same, a tucker-bar arranged transversely over the feed-opening below the free end of the arm and the brackets and 65 pivoted to the free end of said arm and provided at its ends with bearing-ears, springs interposed between the brackets and the ends

of the tucker-bar, a tucker roll having its axis journaled in the ears and projecting therefrom, and a pair of arms pivoted to the inner 70 sides of the chamber and at their free ends connected to the axis of the tucker-roll, substantially as specified.

2. In a baling-press, the combination with a baling-chamber having a feed-opening in its 75 upper side, of brackets extending forward over the opening, an arm pivoted to the chamber and extending forward between the brackets, a tucker-bar arranged under the brackets and pivoted to the free end of the arm, and 80 coiled springs interposed between the upper side of the bar and the under sides of the brackets and means to prevent forward movement of the tucker-bar, substantially as specified. 85

3. In a baling-press, the combination with a baling-chamber, a plunger having a beam, means for operating the plunger in one direction, and a spring for returning the same, of a pivotal link connected at one end to the 90 plunger-beam and provided beyond its connection with said beam with a convexed shoe, and a buffer-spring arranged in the path of the shoe on the link and curved eccentrically with relation to the pivotal point of the later, substantially as specified. 95

4. In a baling-press, the combination with a baling-chamber, a plunger having a beam, means for operating the plunger in one direction, a spring for returning the same, and 100 a pivotal link connected at one end to the plunger-beam and provided with a friction-shoe, of a curved buffer-spring arranged in the path of the spring on said link and disposed eccentrically with relation to the pivotal point of the link, and means for varying the eccentricity of said spring, substantially as specified. 105

5. In a baling-press, the combination with the baling-chamber, the plunger and its beam, 110 a link pivoted to the outer end of the beam, a friction-shoe carried by the end of the link, the opposite end of said link being pivoted to the fixed part of the machine, of means for actuating the plunger in one direction, a 115 spring for returning the same, a segmental-arm arranged upon the framework, a curved spring-buffer plate secured at one end to the arm and located at the inner side thereof in the path of the shoe and eccentrically with relation to the point of pivot of the link and 120 means for varying the eccentricity of said spring buffer-plate, substantially as specified. 125

6. In a baling-press, the combination with the baling-chamber, the plunger and its beam, 125 a link pivoted to the outer end of the beam, a friction-shoe carried by the end of the link, the opposite end of said link being pivoted to the fixed part of the machine, of means for actuating the plunger in one direction, a 130 spring for returning the same, a segmental arm arranged upon the framework, a curved spring-buffer plate secured to the arm and located at the inner side thereof in the path of

the shoe and eccentrically with relation to the point of pivot of the link, and a spring interposed between the free end of the plate and the arm, substantially as specified.

- 5 7. In a baling-press, the combination with the baling-chamber, the plunger and its beam, a link pivoted to the outer end of the beam, a friction-shoe carried by the end of the link, the opposite end of said link being pivoted to 10 the fixed part of the machine, of means for actuating the plunger in one direction, a spring for returning the same, a segmental arm arranged upon the framework, a curved spring buffer-plate secured to the arm and located at the inner side thereof in the path of the shoe and eccentrically with relation to the point of pivot of the link, a set-screw threaded in a perforation in the arm, and a coiled-spring interposed between the end of 15 20 the set-screw and the free end of the plate, substantially as specified.

8. In a baling-press, the combination with the baling-chamber, the plunger-head, the beam, the return-spring, means for actuating

- 25 the plunger-beam, a bifurcated socket arranged on the end of the beam, a vertical pin arranged in the bifurcated socket, a loose roller arranged on the upper end of the pin, a link pivoted on the pin and having at its 30 outer end a friction-shoe and at its opposite end pivoted to the fixed part of the framework, of a segmental arm supported on the frame, and embracing the end of the plunger, and a curved spring-plate secured to the 35 arm and located in the path of the friction shoe, and means for adjusting the plate, substantially as specified.

9. In a baling-press, the combination with a baling-chamber, a plunger and its beam, an 40 anti-friction roll arranged at the rear end of the plunger beam, and a return spring connected to the beam, of a longitudinally disposed bracket 32 having a post 31, a link 42

having a head 43 mounted in the bracket in rear of said post and pivotally connected to 45 the rear end of the plunger-beam, means for cushioning the backward movement of the plunger beam and the movable end of the link, and an intermediately pivoted lever 35 mounted upon the post 31, said lever having opposite compoundly curved arms provided with depending compoundly curved flanges 37 adapted to engage successively with the anti-friction roll carried by the plunger-beam, the outer portions of said flanges being forwardly 50 convexed and the inner portions thereof being forwardly concaved and terminating at intervals from the hub of the lever, whereby as the lever is turned continuously upon its fulcrum the convexed portions of the flanges 55 engage the anti-friction roll on the plunger-beam and advance the latter until the link 42 draws the rear end of the plunger beam inward or toward the fulcrum of the lever sufficiently to cause said roll to pass between the 60 concaved portions of the flanges and the hub of the lever, substantially as specified.

10. In a baling-press, the combination with a baling-chamber provided at its opposite sides with horizontal slots, a plunger, and operating connections, of U-shaped casings arranged in said slots, cross-strips 57^a arranged across the outer sides of said casings, detents pivotally mounted in the casings and arranged in the slots in the walls of the baling-chamber, yokes 12, and springs 13 between the outer sides of the detents and the yokes, substantially as specified.

In testimony that I claim the foregoing as my own I have hereto affixed my signature in 80 the presence of two witnesses.

CHARLES HARMAN FIELD.
